UNITED STATES PATENT OFFICE.

ALEXANDER DURAND, OF LOS ANGELES, CALIFORNIA.

TAILOR'S IRON.

1,180,114.

Specification of Letters Patent. Patented Apr. 18, 1916.

Application filed May 10, 1915. Serial No. 27,269.

To all whom it may concern:

Be it known that I, ALEXANDER DURAND, a citizen of the United States, residing at Los Angeles, in the county of Los Angeles and State of California, have invented a new and useful Tailor's Iron, of which the following is a specification.

My invention relates to tailors' irons, and the principal object of my invention is to provide means in such an iron for supplying steam to the fabric which is being pressed.

A further object of the invention is to provide steam producing means in the iron and to provide valve means for controlling the flow of water into said steam producing means, so that there is no danger of an excess of water being admitted thereto.

A still further object of the invention is to provide a novel form of check valve which will prevent the steam which is generated in the iron from flowing back through the water channels, this check valve allowing considerable steam pressure to be produced and insuring that the steam so produced flows through the toe of the iron to the fabric being pressed.

Referring to the drawings, which are for illustrative purposes only: Figure 1 is a plan view of a preferred form of my iron. Fig. 2 is a partial section on the plane x^2-x^2 of Fig. 1. Fig. 3 is a view of the toe of the iron as seen from below in Fig. 2. Fig. 4 is an enlarged section of the valve means and the supporting structure therefor.

In the form of my invention illustrated in these drawings, 11 is the body of a tailor's iron, an electrically heated iron being shown for illustrative purposes, although my invention may be applied to irons having other heating means. In the iron shown, an electric heating element 12 is provided adjacent to the bottom 13, this heating element being clamped between the bottom 13 and a backing block 14 by means of screws 15. The backing block 14 serves as a heat storage means for the heating element 12. A cover 16 is secured on top of the body 11 by means of screws 17, and a plug attachment 18 provides for a connection between the electrical conductors 19 and suitable terminals attached to the heating element 12, such heating element, plug, and terminals being old in the art and forming no part of the present invention.

A steam generator 20 is secured by means of screws 21 on the top of the backing block

14, this generator 20 being preferably formed of copper and being steam tight, except for openings 22 and 23 which are formed in the top thereof. A pipe 24 is 60 screwed in the opening 22 and is connected by means of a coupling 25 with a pipe 26 which extends downwardly and is threaded into an opening 27 in a tip 28, the tip 28 being formed in the body 11 of the iron 65 or being secured around the front of the iron by any suitable means not shown. A steam channel 29 extends around inside the tip 28 and a plurality of narrow slots 30 extend through the bottom of the tip, connecting the steam channel 29 with the outer air. A nipple 31 is screwed into the opening 23, this nipple having an opening 31 extending therethrough. A ball 32 is placed in the opening 31 and is secured in place by 75 a pin 33, the ball being so located that it seats against a conical seat 34 whenever pressure is applied from below. The nipple 31 has a coupling 35 threaded on the upper end thereof, this coupling being threaded 80 on a valve body 36 which has a manual valve seat 37 formed on the lower end thereof. A manual valve 38 is normally seated thereon, closing an opening 39 extending upwardly therethrough. A valve 85 stem 40 is threaded into the manually operated valve 38 and is also threaded onto a piston 41, this piston sliding in a cylinder 42 formed in the valve body 36, the piston 41 having a compression spring 43 placed 90 thereunder, this spring tending to force the piston 41, the valve stem 40, and the valve 38 into its upper position, as shown in the drawings. A pipe 44 is tightly secured in a cover 45 which is screwed on the valve body 36, closing the top thereof. A small hole 46 is drilled through the piston 41 for the purpose of providing open communication between the interior of the pipe 44 and the interior of the cylinder 42 below the 95 piston 41. The pipe 44 is threaded into a handle valve body 47, this body having a vertical opening 48 through which the valve stem 41 extends, and having a horizontal opening 49 in which is secured a water supply pipe 50. The valve stem 40 passes through packing 51, this packing being compressed by a follower 52. An operating button 53 is secured on the valve stem 40, projecting slightly above the surface of the valve body 47 in a position where it can be conveniently depressed by the thumb of 100 105 110

the operator. The pipe 50 extends rearwardly through a standard 54 formed on the top 16, and connects to a water supply pipe 55 which may be secured to a continuous source of water supply through a flexible hose, or which may be provided with a receptacle in which a supply of water is carried. A front standard 56 also extends upwardly from the top 16, and the casting 47 5 is secured therein by means of a nut 57 threaded on a stud 58 formed on the handle casting 47.

The method of operation of my invention is as follows: Electric current being 15 supplied through the conductors 19, water is supplied through the pipe 55, the water passing through the pipe 50 into the opening 48 in the body 47. This water is free to pass downwardly through the pipe 44 20 and passes slowly through the small opening 46 in the piston 41 into the interior of the cylinder 42, this cylinder forming a water storage reservoir in which a charge of water is allowed to slowly accumulate. Whenever 25 the operator wishes to pass steam to the article being pressed he depresses the button 53, forcing the water in the storage space downwardly past the manually operated valve 38 which is depressed from its seat 30 through the valve stem 40. The charge of water passes through the coupling 35 and the opening 31 in the nipple 30, passing by the ball 32 into the interior of the steam generator 20. The backing block 14 being 35 heated by the heating element 12, the charge of water falls on a hot surface and is turned to steam, generating a slight steam pressure in the interior of the steam chamber 20. This steam pressure raises the ball 32 40 against its seat so that the opening 31 is closed, the steam pressure being retained in the steam chamber 20 by this means. This steam pressure is relieved by the steam flowing through the pipe 24, coupling 25, and 45 the pipe 26 into the interior of the steam channel 29 from whence it passes through the slots 30 into the goods which are being pressed. The operator, as soon as he has passed the charge of water to the interior 50 of the steam chamber 20, releases his pressure on the button 53, the valve 38 assuming its initial position and allowing a supplemental charge of water to be collected in the storage space. Whenever more water is desired, the operator again presses down on the button 53, the steam pressure having been in the meantime relieved by the passage of steam to the fabric being pressed. As soon as the button 53 has depressed an- 55 60 other charge of water is passed into the

steam chamber 20 as previously explained. As the opening 46 is very small, it is impossible for the operator to flood the iron with an excess of water, and at the same time it is possible for him to supply steam intermittently by means of the button 53. 65

I claim as my invention:

1. A tailor's iron comprising a body, means for heating said body, a steam generator in said body, means for passing steam 70 from said generator to the goods to be pressed, a water storage reservoir carried by the iron, means for supplying water at a restricted rate to said water storage reservoir, and means controlled by the operator 75 for passing the water from said water storage reservoir into said steam generator.

2. A tailor's iron comprising a body, means for heating said body, a steam generator in said body, means for passing steam 80 from said generator to the goods to be pressed, a water storage reservoir carried by the iron, means for supplying water at a restricted rate to said water storage reservoir, means controlled by the operator for 85 passing the water from said water storage reservoir into said steam generator, and a check valve for preventing the steam generated from said steam generator from flowing to said water storage reservoir. 90

3. In a tailor's iron a valve structure comprising a valve body having a cylindrical bore therein, a piston in said bore having a minute water opening therein, a spring for holding said piston at one end of said bore, 95 means for supplying water to the same end of said bore above said piston, outlet means for conducting water from the other end of said bore, and a manually operable valve for normally closing the passage through said 100 outlet means.

4. In a tailor's iron a valve structure comprising a valve body having a cylindrical bore therein, a piston in said bore having a minute water opening therein, a spring 105 for holding said piston at one end of said bore, means for supplying water to the same end of said bore above said piston, outlet means for conducting water from the other end of said bore, a manually operable valve 110 for normally closing the passage through said outlet means, and a check valve in the passage through said outlet means so arranged as to prevent fluid from flowing through said outlet means into said cylinder. 115

In testimony whereof, I have hereunto set my hand at Los Angeles, California, this 1st day of May, 1915.

ALEXANDER DURAND.
